UNITED STATES PATENT OFFICE.

SAMUEL W. RUFF, OF GACKLE, NORTH DAKOTA.

ROPE-CLAMPING DEVICE.

1,322,956.

Specification of Letters Patent.

Patented Nov. 25, 1919.

Application filed June 4, 1918. Serial No. 238,149.

To all whom it may concern:

Be it known that I, SAMUEL W. RUFF, a citizen of the United States, residing at Gackle, in the county of Logan, State of North Dakota, have invented a new and useful Rope-Clamping Device; and I do hereby declare the following to be a full, clear, and exact description of the invention, such as will enable others skilled in the art to 10 which it appertains to make and use the same.

This invention relates to an improved rope holding or clamping device.

In selling rope in general stores, where 15 merchandise, hardware, implements and the like are sold, the reel of rope is disposed in basement and the end of the rope is passed up through the floor. When certain lengths of rope are sold they are measured off, and 20 when cut or severed from the main body of the rope, it very often occurs that the end of the rope is allowed to pass down through the opening in the floor, requiring the salesman to leave the customer and go into the 25 basement and repass the end of the rope through the opening in the floor.

An object of the present invention is to provide a device for securely holding or clamping the end of the rope, preventing it 30 from dropping into the basement, and consequently overcoming the foregoing disadvantages.

A further object of the invention is to provide a tubular holder for the rope, a spring 35 clamping device engaging through an opening in the wall of the tubular holder to clamp or bind against the rope, in combination with means carried by the tubular holder slidably for releasing the spring 40 clamping device.

In practical fields the details of construction may necessitate alterations falling within the scope of what is claimed.

The invention comprises further features 45 and combination of parts as hereinafter set forth shown in the drawings and claimed.

In the drawings:—

Figure 1 is a view in plan of the improved holder or clamp constructed in accordance 50 with the invention.

Fig. 2 is a sectional view on line 2—2 of Fig. 1.

Fig. 3 is a sectional view similar to Fig. 2, but showing the spring clamping device as

having been actuated by a member and dis- 55 engaged from the rope.

Fig. 4 is an enlarged detail perspective view of the holder.

Referring more especially to the drawings 1 designates a tubular member or 60 holder, one end of which is flared outwardly, thereby providing a bead or marginal roll 2; the other end is provided with a circular disk flange 3. The tubular holder or member is designed to engage through a hole or 65 opening 4 of the wall or floor, whereby the circular disk flange 3 may be secured by screws 5 to the wall or floor 6. The end of the rope 7 passes through the tubular holder or member 1, as shown clearly in Figs. 1 to 70 3 of the drawings. The tubular member or holder has an elongated opening 8, and secured at 9 to the holder is a spring clamping device 10. The end portion of the spring clamping device 10 normally curves 75 downwardly through the opening or slot 8, whereby the lug 11 and the free end 12 of the clamping device may engage or bite into the rope normally as shown in Fig. 2. A slide bar 13 is mounted in an opening 14 80 of the circular disk and the arched guide 15, which is carried by the tubular member or holder. This bar 13 has an elongated slot or opening 16, through which the spring device 10 also engages, thereby additionally 85 guiding the slide bar. The outer end of the slide bar has an upturned hook 17. When it is desired to cut or sever a piece of rope, and also measure the same, the slide bar 13 is pulled outwardly, and in so actuating said 90 bar the end edge 18 of the slot or opening will cam against the spring device 10, and lift the end portion 12 of the spring device, sufficiently, so that said end and the lug 11 will be disengaged from the rope. The rope 95 is then free to be pulled through the tubular holder and measured off, and before cutting the rope the slide bar 13 may be pushed inwardly, allowing the end of the spring device to engage the rope, and after which the 100 rope may be severed. In this manner the severed end of the rope is prevented from falling into the basement, as in the old way.

The invention having been set forth what is claimed as new and useful is:—

1. In a rope clamp, a tubular rope receiving member having in its wall an elongated opening and adapted to be fixed through a

stationary support, a spring clamping device normally engaging through the opening and biting against said rope, and a slide bar mounted in guides of the tubular holder to 5 actuate the spring clamping device to raise the same out of the opening and disengage it from the rope.

2. The combination with a tubular rope receiving holder, of means for securing the 10 same through a stationary support, the wall of said holder having an elongated opening, a spring clamping device fixed to the holder and having its free end extending through the opening and engaging the rope, a slide bar mounted in guides of the tubular holder 15 and provided with an opening at one end through which the spring clamping device engages, whereby as the slide bar is moved

the spring clamping device will be lifted from the opening of the holder so that the 20 free end may disengage the rope.

3. In a rope clamp, a tubular rope receiving member having in its wall an elongated opening and adapted to be fixed to a stationary support and a spring clamping arm carried by the tubular rope receiving member and extending through said elongated opening 25 for clamping the rope.

In testimony whereof I have signed my name to this specification in the presence of 30 two subscribing witnesses.

SAMUEL W. RUFF.
